Specification of Letters Patent. Patented June 30, 1914.

Application filed March 11, 1914. Serial No. 824,021.

To all whom it may concern:

Be it known that I, HENRY L. BETTEN, a citizen of the United States, residing at Alameda, in the county of Alameda and State of California, have invented certain new and useful Improvements in Monkey-Wrenches, of which the following is a specification, reference being had to the accompanying drawings.

This invention relates to certain improvements in monkey wrenches and has relation more particularly to a device of this general character wherein the clamping jaw has a sliding movement independently of the adjustment by which the jaw is caused to firmly clamp the work; and an object of the invention is to provide a device of this general character having novel and improved means whereby a sliding adjustment of the clamping jaw may be afforded with convenience and facility and whereby such clamping jaw is effectively maintained in its various sliding adjustments.

The invention also has for its object to provide a novel and improved device of this general character including a lever coacting with the clamping or sliding jaw which allows the inward pressure of the clamping or sliding jaw to be applied at a point far enough distant from the clamping or sliding jaw to avoid undue tilting and consequent binding of the checking or locking agency whereby such clamping or sliding jaw is locked in its various adjustments.

The invention consists in the details of construction and in the combination and arrangement of the several parts of my improved monkey wrench whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Fig. 1 is a view, partly in elevation and partly in section, of a wrench constructed in accordance with an embodiment of my invention; Fig. 2 is a sectional view taken substantially on the line 2—2 of Fig. 1; Fig. 3 is a view in perspective, detached, of a de-

tail of my invention as herein disclosed; and Fig. 4 is a fragmentary view in front elevation of the device as herein disclosed, illustrating certain details.

As disclosed in the accompanying drawings, 1 denotes the shank of my improved wrench having produced in its opposite sides, the longitudinally directed grooves 2 open at one end of such shank while the opposite extremity of the shank is provided with the stationary jaw 3, with which is adapted to coact the clamping or sliding jaw 4 mounted for endwise movement upon the shank 1. The jaw 4 is provided with a bore 5 through which the shank 1 is adapted to be directed and the opposite side walls of such opening or bore being provided with the inwardly directed tongues or shoulders 6 adapted to project within the grooves or channels 2 produced in the shank 1 whereby it will be perceived that the jaw 4 is maintained substantially against lateral or transverse movement. The forward face of the jaw 4 is provided with the transverse slot 7 intersecting the longitudinally directed recess 8 produced in the outer face of the jaw 4 and into which is adapted to be projected the threaded shank 9, such threaded shank 9 being engaged by the adjusting nut or wheel 10 operatively positioned within the slot 7, the outer surface or periphery of such nut or wheel 10 being milled or serrated, for a purpose which is believed to be self-evident. The outer portion of the recess 8, as indicated at 11, is enlarged in order to accommodate the head 12 of the threaded shank 9, which head 12 has its outer extremity projected exteriorly of the jaw 4 and has its outer end rounded, as indicated at 14.

The inner longitudinal edge of the shank 1 is provided with the series of teeth 15 extending a predetermined distance longitudinally thereof, with the inner tooth thereof spaced a predetermined distance from the stationary jaw 3 and surrounding the shank 1 is the sleeve 16, the bore whereof being greater than the width of the shank 1, as is clearly shown in Fig. 1, one wall of such sleeve being provided with a series of teeth 18 adapted to interlock with the teeth 15 in order to maintain the sliding jaw 4 against movement longitudinally of the shank 1, as will hereinafter be more fully set forth, independently of the adjustment of such jaw 4 as afforded by the threaded shank 9 and its

concomitant parts. The teeth 18 are normally maintained in mesh with the teeth 15 through the tension exerted by the double leaf spring 19 suitably anchored, as at 20, to the outer end of the sleeve 16 intermediate its length and having its extremities contacting with the unobstructed or outer edge of the shank 1, as is clearly shown in Fig. 1, it being readily perceived that the teeth 18 10 may be freed from the teeth 15 by forcing the sleeve 16 against the tension of the spring 19, which may be done with convenience and facility by a digit of the hand grasping the shank 1.

15 While the teeth 18 may be produced directly upon the sleeve 16, I prefer to have the same formed on a removable block or insert 21, particularly illustrated in Fig. 3, which block or insert 21 being produced in 20 its face with the transverse open ended slot or groove 22 adapted to coact with a similarly disposed inwardly directed shoulder or tongue 23 produced on the inner wall of the sleeve 16 whereby it will be readily perceived that such block or insert 21 is properly maintained in operative position. To further assure against displacement of this block or insert 21, I find it of advantage to provide at one end thereof the extension 24 25 provided with openings 25 through which suitable anchoring means 26 may be directed, such anchoring means also coacting with the sleeve 16, which sleeve, of necessity, must be provided with openings adapted to 30 register with the openings 25 of the block or insert 21 when the same is in assembled position. By use of the block or insert 21, it will be perceived that the teeth 18 may be tempered to the degree insuring greatest resistance to wear and strain, which treatment is also given to the teeth 15 on the shank 1.

35 Integrally produced with the sleeve 16 and projecting toward the stationary head 3 on a predetermined incline in a direction 40 away from the inner edge of the shank 1 is the lever or extension 27 having its free extremity provided with the perforate spaced ears 28 adapted to accommodate therebetween the projected extremity of the head 45 50 12, such ears and head having directed therethrough a suitable pin or pintle 29 whereby it will be readily perceived that a pivotal engagement is created between the lever or extension 27 and the head 12 whereby the 55 sleeve 16 may be operated with greater convenience and facility whereby it will be perceived that the inclination of the extension or lever 27 is such as to assure an effective locking engagement between the teeth 15 and 60 18 when the improved monkey-wrench is in actual use.

In order that the pintle or pin 29 may be substantially freed from the pressure or strain created when the device is in operation, I find it of advantage to have the end

of the extension or lever 27 between the ears 28, as indicated at 30, concaved to firmly abut the rounded end 14 whereby it will be readily perceived that the strain or pressure, when the wrench is in use, is upon the extension or lever 27 and the head 12 substantially independent or free of the pin or pintle 29.

In order to maintain the shank 9 in operative position, I find it of advantage to provide in a face of the head 12 adjacent the inner end portion thereof, the elongated longitudinally disposed recess 31 into which projects a finger 32, operating in a manner which is believed to be self-evident.

From the foregoing description, it is thought to be obvious that a monkey wrench constructed in accordance with an embodiment of my invention is of an extremely simple and comparatively inexpensive nature and is particularly well adapted for use by reason of the convenience and facility with which it may be assembled and by reason of the effectiveness with which it performs its various functions, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A device of the character described including a shank having teeth on one edge and a fixed jaw, a movable jaw slidably mounted upon the shank, a sleeve slidably mounted upon the shank below the movable jaw, the bore of the sleeve being in excess of the width of the shank, such sleeve being provided with teeth adapted to engage the teeth of the shank, means for maintaining the teeth of the sleeve normally in engagement with the teeth of the shank, an elongated member carried by the movable jaw, an extension carried by the sleeve in pivotal engagement with the elongated member, and means coacting with the movable jaw and the elongated member whereby such movable jaw may be moved endwise of the shank independently of the movement afforded when the teeth of the sleeve and the teeth of the shank are disengaged.

2. A device of the character described including a shank having teeth on one edge and a fixed jaw, a movable jaw slidably mounted upon the shank, a sleeve slidably mounted upon the shank below the movable jaw, the bore of the sleeve being in excess of the width of the shank, such sleeve being provided with teeth adapted to engage the teeth of the shank, means for maintaining the teeth of the sleeve normally in engage-

ment with the teeth of the shank, an elongated member carried by the movable jaw, an extension carried by the sleeve in pivotal engagement with the elongated member, and means coacting with the movable jaw and the elongated member whereby such movable jaw may be moved endwise of the shank independently of the movement afforded when the teeth of the sleeve and the teeth of the shank are disengaged, such shank being provided on opposite faces with longitudinally disposed channels, the sliding jaw being provided with shoulders adapted to be accommodated within the grooves of the shank.

3. A device of the character described including a shank having teeth on one edge and a fixed jaw, a movable jaw slidably mounted upon the shank, a sleeve slidably mounted upon the shank below the movable jaw, the bore of the sleeve being in excess of the width of the shank, a block insertible within the sleeve and provided with teeth adapted to interlock with the teeth of the shank, means for maintaining such block in operative position, means for maintaining the teeth of the block normally in engagement with the teeth of the shank, an elongated member carried by the movable jaw, an extension carried by the sleeve in pivotal engagement with the elongated member, and means coacting with the movable jaw and the elongated member whereby such movable jaw may be moved endwise of the shank independently of the movement afforded when the teeth of the block and the teeth of the shank are disengaged.

20 4. A device of the character described including a shank having teeth on one edge and a fixed jaw, a movable jaw slidably mounted upon the shank, a sleeve slidably mounted upon the shank below the movable jaw, the bore of the sleeve being in excess of the width of the shank, a block insertible within the sleeve and provided with teeth adapted to interlock with the teeth of the shank, means for maintaining such block in operative position, means for maintaining the teeth of the block normally in engagement with the teeth of the shank, an elongated member carried by the movable jaw, an extension carried by the sleeve in pivotal engagement with the elongated member, and means coacting with the movable jaw and the elongated member whereby such movable jaw may be moved endwise of the shank independently of the movement afforded when the teeth of the block and the teeth of the shank are disengaged.

25 5. A device of the character described including a shank having teeth on one edge and a fixed jaw, a movable jaw slidably mounted upon the shank, a sleeve slidably mounted upon the shank below the movable jaw, the bore of the sleeve being in excess of the width of the shank, a block insertible within the sleeve and provided with teeth adapted to interlock with the teeth of the shank, means for maintaining such block in operative position, means for maintaining the teeth of the block normally in engagement with the teeth of the shank, an elongated member carried by the movable jaw, an extension carried by the sleeve in pivotal engagement with the elongated member, and means coacting with the movable jaw and the elongated member whereby such movable jaw may be moved endwise of the shank independently of the movement afforded when the teeth of the block and the teeth of the shank are disengaged.

30 6. A device of the character described including a shank having teeth on one edge and a fixed jaw, a movable jaw slidably mounted upon the shank, a sleeve slidably mounted upon the shank below the movable jaw, the bore of the sleeve being in excess of the width of the shank, a block insertible within the sleeve and provided with teeth adapted to interlock with the teeth of the shank, means for maintaining such block in operative position, means for maintaining the teeth of the block normally in engagement with the teeth of the shank, an elongated member carried by the movable jaw, an extension carried by the sleeve in pivotal engagement with the elongated member, and means coacting with the movable jaw and the elongated member whereby such movable jaw may be moved endwise of the shank independently of the movement afforded when the teeth of the block and the teeth of the shank are disengaged.

35 7. A device of the character described including a shank having teeth on one edge and a fixed jaw, a movable jaw slidably mounted upon the shank, a sleeve slidably mounted upon the shank below the movable jaw, the bore of the sleeve being in excess of the width of the shank, a block insertible within the sleeve and provided with teeth adapted to interlock with the teeth of the shank, means for maintaining such block in operative position, means for maintaining the teeth of the block normally in engagement with the teeth of the shank, an elongated member carried by the movable jaw, an extension carried by the sleeve in pivotal engagement with the elongated member, and means coacting with the movable jaw and the elongated member whereby such movable jaw may be moved endwise of the shank independently of the movement afforded when the teeth of the block and the teeth of the shank are disengaged.

the teeth of the block and the teeth of the shank are disengaged.

4. A device of the character described including a shank having teeth on one edge and a fixed jaw, a movable jaw slidably mounted upon the shank, a sleeve slidably mounted upon the shank below the movable jaw, the bore of the sleeve being in excess of the width of the shank, a block insertible within the sleeve and provided with teeth adapted to interlock with the teeth of the shank, means for maintaining such block in operative position, such block being provided on its inner face with a recess, the adjacent face of the sleeve being provided with a shoulder adapted to project within the recess of the block, means for maintaining the teeth of the block normally in engagement with the teeth of the shank, an elongated member carried by the movable jaw, an extension carried by the sleeve in pivotal engagement with the elongated member, and means coacting with the movable jaw and the elongated member whereby such movable jaw may be moved endwise of the shank independently of the movement afforded when the teeth of the block and the teeth of the shank are disengaged.

In testimony whereof I hereunto affix my signature in the presence of two witnesses. 65
